UNITED STATES PATENT OFFICE

ALFRED G. F. KUROWSKI, OF BROOKLYN, NEW YORK, ASSIGNOR TO UNDERWOOD
ELLIOTT FISHER COMPANY, OF NEW YORK, N. Y., A CORPORATION OF DELAWARE

COMBINED TYPEWRITING AND CARD-PERFORATING MACHINE

Application filed July 21, 1928. Serial No. 294,347.

The invention relates to a combined type-writing and card-perforating machine. The perforating machine or punch, being of the Powers type, forms a separate unit electrical-
ly controlled from the typewriter unit. It
operates simultaneously with the typing of
a record upon a work-sheet, and perforates
cards so as to give a record of certain data.

The invention relates more particularly to
10 automatic means or a master switch for con-
necting and disconnecting the two units at
proper times.

Heretofore it was required to manipulate
an electric switch so as to render the punch
15 operative, while a selected stretch or zone
of the work-sheet passed the typing line.
This involved serious mistakes, an operator
being liable to condition a machine at inop-
portunite times.

20 The invention provides a switch including
a contact face which moves under the control
of the rotary platen, and which is timed in
such a manner with the platen rotation that
the punch will be allowed to work during
25 a selected interval of platen rotation only,
to coincide with said selected zone upon the
work-sheet. Before and after this interval,
the typewriter may be operated in the ordi-
nary manner.

30 The master switch includes preferably a
disk of insulating material which is pivoted
upon the platen-frame adjacent the platen-
shaft and suitably geared up to the platen-
shaft. Part of the cylindrical face of the
35 disk is formed with a metal contact face
to close a circuit, as it travels past two rela-
tively stationary brushes or terminals. The
gears and the contact face are suitably di-
mensioned and arranged so that the circuit is
40 closed during the required interval of platen
rotation.

The gearing may be speed-reducing so that
a working zone requiring a plurality of plat-
en rotations will cause less than a full revo-
45 lution of the contact disk. In other words,
during a plurality of platen rotations the
contact disk will be allowed to move only
once through its operating zone, so that any
length of the working zone may be taken care
50 of.

The novel switch is useful in a method of
operation, whereby the leading edge of a
form will be inserted between the feed-rolls
and the platen by means, for instance, of
a well-known geared inserter. The form
55 may thus be brought to the first writing line,
while the Powers punch is still disconnected.
After completing the writing in the usual
heading, the form will be advanced to the first
writing line in the body thereof, which simul-
60 taneously connects the Powers punch, which
is to remain in operation until the form is
completed. By rotating the platen the form
may now be returned until free from the
feed-rolls and the platen-cylinder against a
65 definite stopping position. This leaves the
machine in correct position for inserting the
next form so that contact will be made again
at the proper time.

Since the contact disk will preferably not
70 perform more than one revolution, the
means required to stop the platen at the ini-
tial position may be suitably arranged in the
form of lugs between said disk and the
platen-frame.

75 Another feature relates to means for fine
adjustment in timing the switch. To this
end, the stationary brushes are made adjust-
able so as to advance or retard the switching
period.

80 Other features and advantages will herein-
after appear.

In the accompanying drawings,

Figure 1 shows the main operating parts
of an Underwood typewriter and a Powers
85 punch, both being electrically connected by
a cable.

Figure 2 is a detail side view upon the
platen-carriage showing the novel platen-
controlled main switch as geared up to the
80 platen-shaft.

Figure 3 is a semi-diagrammatical view
of parts to illustrate the operation of the
electrical equipment.

Figure 4 shows, in perspective, the details
95 of the novel automatic main switch, parts
drawn apart to show their mounting and
mutual relation.

On a typewriter having a main frame 10
are mounted numeral-keys 11, and alphabet- 100

keys, not shown. When depressed these keys swing key-levers 12 about a fulcrum 13, to actuate bell-cranks 14, to swing type-bars 15 upwardly and rearwardly against the front 5 of a rotary platen 16. The platen is carried by a shaft 17, journaled in a carriage 18 which travels upon carriage-rails 19 and 20 mounted on the main frame 10. Work-forms 21 are successively introduced at the rear of 10 the platen and fed around it by the usual means including feed-rolls 22 and a knob 23, or ratchet 23^a. The platen is used in line-feeding the work-sheet, but any other rotary line-feeding means may be used.

15 The carriage 18 is pulled from left to right by a spring-motor 24 connected to the carriage by a strap 25. The type-bars engage a universal-bar 26 movable rearwardly to actuate an escapement-rocker 27 carrying escapement-dogs 28 co-operating with the teeth 20 of an escapement-wheel 29, to effect step-by-step movements of the carriage by the operation of any numeral-key 11, or of the alphabet-keys or space-bar, not shown. The 25 escapement wheel is connected to, and is rotated by, a pinion 30 driven by a feed-rack 31 supported by arms 32 pivoted to the carriage-frame.

The tabulating mechanism, partly shown 30 herewith, is well-known and includes a tabulator-key 33 pivoted on the fulcrum 13 and provided with a draw-link 34 connecting with a rocking frame 35 carrying a series of stops 36. By depressing the tabulator-key these 35 stops are actuated into the path of a carriage-stop 37, and concurrently the carriage-feed-rack 31 is disengaged from the pinion 30 by means not shown, and the spring-motor 24 effects column-skipping or tabulating. A 40 usual brakepad 38 is attached to the carriage-frame and engages an upper chord 39 of the rocking frame 35 through the depression of the tabulator-key, thus checking the travelling speed of the carriage.

45 Power-driven means for returning the typewriter-carriage may include an electric motor 40 geared to a clutch-member 41 which is keyed on a normally-rotating shaft 42. On the latter also is the slidably mounted 50 pinion 30 having an attached clutch, not shown, which has teeth to engage the clutch-member 41. The clutch-pinion 30 is normally in mesh with the feed-rack 31 which is attached to the carriage by the arms 32. 55 When the carriage has taken its last letter-spacing step the clutch-members are automatically engaged and the pinion acts through the rack to return the carriage to the right-hand end of its travel, where the 60 clutch-members are automatically disengaged, and the carriage comes to rest. A carriage-return movement may also be initiated at any time through the depression of a trip-key, not shown, which acts to engage the clutch-members. When not op-

erating the typewriter, the motor 40 is ordinarily cut out by a switch, not shown.

In use with the above described typewriter 70 is a Powers key-punch or card-perforating machine which is synchronized with the typewriter and is electrically operated thereby. The key-punch is a separate unit, controlled through an electric cable, and so perforates the card as to give a graphic record of certain data typed on the work-form 21. In effecting this the key-punch completes successive cycles of operation concurrently with the governing typing machine. As in the latter, such cycles may be automatically initiated, or may be initiated by the trip-key. 75

The Powers key-punch has a main frame generally indicated by 43 which supports an electric motor, not shown, and normally rotating. Such motor may have a separate switch or may be controlled by the same switch which governs the typewriter carriage-return motor 40. In connection with the key-punch motor is an electrically-operated clutch, not shown, which can engage a stub-shaft 44. The latter is automatically 80 disengaged from the clutch at the end of each complete revolution.

On the stub-shaft 44 is a driving gear 45 which intermittently rotates feed-rolls 46, 47 and 48, and ejector rolls 49. Also on the stub-shaft 44 is a cam 50, having a groove 51 in which is a follower roll 52 mounted on an arm 53. The latter is attached intermediate the ends of a rocker-bar 54, pivoted in a main frame at 55. The rocker-bar carries arms 56 which engage slideable journals 57 and through which a vertically reciprocable sliding frame 58 may be actuated. Also on the stub-shaft is a cam 59 with a follower roll 60 on a lever 61 fulcrumed at 62. The lever 61, through a spring 63, actuates a feed-plate 64 which can slide one card 65 from beneath a stack of cards 66 and position the card to be picked up by the feed-rolls 46. The cards are pressed flat on the feed-plate by a weight 67 within 100 a card-container or guide 68 mounted on the main frame.

The sliding frame 58 carries a die-plate 69 and punches 70, having heads 71. The punches are guided at their upper ends by a fixed plate 72 carried by the main frame 43. The plate 72, through the heads 71, prevents the punches from falling through the die-plate and maintains a space between the latter and the punches for the insertion of a 115 card. The punches usually are in columns of twelve each and with a total of forty-five columns. A super-plate 73 is carried by the vertically sliding frame 58 and guides the lower 120 end of the punches. The super-plate also holds the card down when the punches are withdrawn therefrom and keeps the card flat so its edge may register, to be picked up by the ejector rolls 49.

Supported on the main frame 43 are rails 130

74 on which run rollers 75. These rollers support a travelling frame 76 which is kept down on the rails by holding rolls 77. The travelling frame carries a plate 78 and also 5 has cross-bars 79 and 80 which support other plates 81, 82 and 83. The plates 81, 82 and 83 have rectangular holes which register one above the other and with the heads of the punches 70. In these three plates these holes 10 fit pins 84, each of which registers with an underlying punch. Each pin has a fixed collar 85 and a compression-spring 86. The springs permit the pins to be depressed, but also co-act with the plate 83 to raise the 15 collars against the plate 82 which limits the upward movement of the pins. The pins may be held down through cam-face notches 93 engaging a series of latch bars 94 which are pressed into the notches by springs 95.

20 In the plate 78 are twelve holes that can register with any one column of pins. Through these holes pass plungers 87 which are pivotally supported on bell-cranks 88. The latter are fulcrumed on a shaft 89 and 25 at their free ends abut push pins 90, which slide in a support 91 mounted on the travelling frame 76. Also pivotally mounted on the fulcrum 89 is a universal-bar 92 which is spring pressed against the bell-cranks 88.

30 The universal-bar by such pressure normally keeps the plungers raised and the push pins within their support.

For advancing the travelling frame in a hole-spacing direction, there is a spring motor, not shown, to which is attached a strap 96. The latter is connected to an arm 97 pivoted at 98 to the travelling frame 76. The hole-spacing mechanism includes an escapement-wheel 99 attached to a pinion 100 and mounted on the travelling frame at 101. The pinion rolls along a rack 102 attached to the main frame 43. The escapement-wheel has teeth with a suitable pitch which are engaged by a stepping dog 103 fixed on a shaft 104 and having a pin 105. A holding dog 106 is loosely mounted on the shaft 104 and alongside the stepping dog. The holding dog has an arm 107, a pin 108 and a spring 109 which normally holds the dog 50 in engagement.

When a push pin 90 is projected from its support 91, as will be explained hereinafter, the bell-crank 88 will move the universal-bar 92. The latter, through means not shown, vibrates the escapement-dogs, and hole-spaces the travelling frame each time a numeral-key or the space-bar is depressed. To permit column tabulation on the card-perforator, the usual means are provided to 60 disengage the escapement mechanism. Such means include a lever 110 pivoted at 112 to swing at right angles to the holding dog 106. Said lever has a pin 111 which projects to underlie the pin 108 in said holding dog. The lever 110 is normally held in dis-

engagement with the pin 108 by a spring, not shown.

The lever 110 is pivotally actuated by a bell-crank 113 which is similar to the bell-cranks 88 and which is mounted on the same 70 shaft 89. The bell-crank 113 has an extension 114 which overlies an arm 115 on the lever 110. When the bell-crank 113 is actuated by a push pin 90, the extension 114 depresses the arm 115 of the lever 110, and the pin 111 will raise the pin 108 and disengage the holding dog. The lever 110 is thus maintained by a spring-pressed latch 116 which is pivoted on an ear 117 of said lever. The latch in turn is caught upon a plate 118 and is held thereby during a tabulating movement. At the termination of the latter, a counter stop 119 trips the latch 116, thereby restoring the lever to normal position and permitting the holding dog 106 80 to re-engage the escapement-wheel. The counter stops are mounted on a notched bar 120 supported on the main frame by uprights 121.

Near one end of the platen-shaft 17, and 90 mounted thereon, is a spur gear 122 having a hub 123 with set screws 124. In mesh with the gear 122 is another spur gear 125 which is rotatably mounted on a stud 126. The latter is formed with an annular collar 127, a shoulder 128, and has a large and a small threaded end. Also rotatably mounted on the stud 126 is an insulating disc 129 which is preferably of fiber. On the periphery of the disc, and set into the latter to insure a smooth perimeter, is a metal strip 130 which extends part way around the circumference of the disc.

Mounted on the typewriter-carriage 18 is a plate 131 having a dependent ear 132 which is bored to receive the stud 126. The plate is attached to the carriage by screws 133 which also hold an angle plate 134. The latter is slidably adjustable through slots 135 and is tapped near one end to receive screws 136 which hold an insulating block 137. On the latter rest brushes 138 which are secured to the block by binding screws 139 to which wires 140 are attached. The top of the insulating block may be recessed along opposite edges to maintain the brushes in parallel alignment and thus avoid short circuiting.

The spur gear 125 and the insulating disc 129 are assembled on the stud 126 and are loosely held thereon by a washer 141 and its nut 142. The gear and disc are attached by countersunk screws 143. The plates 131 and 134, and the block 137 are attached to the carriage frame 18, and the stud is attached to the ear through a nut 144. The brushes 138 and the wires 140 are then attached to the block so that when assembled the parts will assume the relative positions shown in Figure 3.

As shown in Figure 3 also, the spur gear 130

125 abuts the metal strip 130. If this gear were of metal a short circuit or ground might result. The gear 125, therefore, may be made of fiber, or an insulator or spacer may be added between said gear and the insulating disc 129. Also shown in Figure 3 is a tongue 145 on the ear 132. This tongue functions as a stop to engage a lug 146 which is attached to a side of the spur gear 125. The purposes of the stop and the lug will be hereinafter explained.

Below the keyboard of the typewriter, and attached to the frame thereof, is a case 147 on which are collars 148. These collars are bored to guide plungers 149, which underlie all the keys, and a spring bar, not shown. The plungers are insulated at their lower ends and rest on bow springs 150 having contacts 151. The bow springs are attached to an insulating plate 152 by binding screws that also hold one wire of a normally open circuit. Other contacts 153 are also carried by the insulating plate and are attached to another wire in the same circuit. The last-mentioned wires, together with the wires 140, are usually gathered into a cable 154 that may be of any convenient length.

One pole of the brushes 138 is connected to a motor-generator 155 and to a series of electro-magnets or solenoids 156, while the other pole is cross-connected to all the contacts 151. From each contact 153 a wire extends to either one or more electro-magnets. The latter have cores 157 that become magnetized and are raised each time the solenoids are energized. These cores are attached to push wires 158 which are slidable in flexible tubes 159. The latter at one end are attached to a case, not shown, which contains the electro-magnets, and at the other end are fixed in the support 91.

This invention pertains particularly to the parts shown in Figure 4, and as assembled with other parts in Figure 3. With these parts is used a work-form 21 which is usually printed, and in its upper portion has captioned spaces in which a name, address and other data are typed. The lower portion contains captioned columns in which classification numerals and various figures or amounts may be typed. The figures on the lower portion of one work-form are often compiled with the figures of many other forms. When this is done mechanically the primary factor used is a card-perforating machine.

With this invention a work-form 21 is rear-
60 inserted in the typewriter, as shown by Figure 2. The work-form is then platen-rolled until its top line assumes a typing position, and the data is typed in on its upper portion. During this typing the usual line-spacing movement has rotated the gears 122 and 125. When the last line has been typed on said
65 upper portion, the attached insulating disc

will then be in the position shown in Figure 3. During such typing the card-perforating machine has not been in operation because not electrically connected to the typewriter.

When the work-form has been advanced 70 into the zone of its lower portion by the line-spacing movement, the insulating disc will also have been advanced thereby in the direction shown by the arrow in Figure 3. Such advancement, which is slight, will, of course, 75 advance the metal strip 130 and cause it to bridge the gap and close the electric circuit, which until then has been open between the two brushes 138. The motor-generator 155 can then energize this circuit as soon as a second gap therein is closed. This second gap interlies the contacts 151 and 153.

When the space-bar or trip-key are depressed, or when a numeral-key 11 or the tabulator-key 33 are depressed, one of said 85 second gaps is closed. Such closure serves to energize one or more solenoids which then function to carry out the desired results in the card-perforating machine. Where a key bearing a single numeral is depressed, one 90 solenoid acts to raise its core 157 which slides its push wire 158 through the tube 159. The push wire in turn projects an abutting push pin 90 against its bell-crank 88, which depresses its plunger 87. The plunger de- 95 presses a pin 84 which, through its notch 93, is caught and held down by a spring-pressed latch-bar 94.

Said numeral-key having been released and the solenoid thus demagnetized, the spring-pressed universal-bar 92 will restore said plunger, bell-crank, push pin, push wire, and core to their former normal positions. Also, upon the release of said key, the typewriter-carriage is letter-spaced and the travelling 100 frame 76 is hole-spaced through its universal-bar 92. If a key having the letters of a word or syllable thereon be actuated the above cycles of setting and releasing are simultaneously inaugurated by two or more 110 solenoids to set two or more pins in any one column. This is accomplished by connecting two or more solenoid circuits to one of the contacts underlying the logotype-key.

By the successive depression of either the space-bar or tabulator-key with the numeral-keys, one horizontal line of figures is eventually typed in the proper columns on the lower portion or zone of the work-form. Each numeral-key depressed has concurrently set its correlative pin in each corresponding column of the card-perforating machine. Underlying these pins an imperforate card has been positioned on the die plate 69. A partial rotation of the shaft 44 raises the die-plate, and the card thereon carries up the punches 70. The punches held down by the pins 84 will then perforate the card. Such punching may be automatic or may be initiated through the trip-key.

A further rotation of the shaft completes its intermittent one revolution, when the die-plate will drop to rest and the card will be released for removal. The card, having been punched, the travelling frame 76 will automatically return to its starting point. During such return the pins will be released by well-known means and the perforating machine left ready for the initiation of another 10 cycle.

The cards which are perforated may have printed captions and column lines, or may be blank and be identified by a hole so positioned as to classify them. The cards are usually 15 stacked in the card-container 68. Before initiation of the typing operations the perforating machine is tripped to cause one revolution of its shaft which positions a card for an ensuing punching operation. After 20 punching, the first card is advanced by the ejector rolls 49 and drops into a card-receptacle 160. The first card is ejected simultaneously with the insertion of a second card which then lies positioned to be punched.

25 During the above cycles of operation one line has been typed in the lower zone of the work-form 21 and one card has been perforated. Other lines may be successively typed in said lower zone until the bottom edge of 30 the work-form is reached. For each of said lines typed one card will be correspondingly perforated. When such typing has been completed the platen is rotated in a reverse direction to that of line-spacing. This will return 35 the work-form to the position shown in Figure 2 where it is free to be removed.

In reversing the rotation of the platen, the gears 122 and 125 will revolve the insulating disc 129, and its metal strip 130 will 40 finally cease to bridge the gap between the brushes 138. This circuit, therefore, is again broken and the perforating machine ceases to function. It will thus lie inoperative until an ensuing work-form has been inserted and 45 advanced to the point where said metal strip again bridges said gap.

This invention is most advantageously used when the gears 122 and 125 are proportioned according to the zones of the work-form used. 50 With a proper gear ratio there will be little lost motion in advancing or retracting the work-form between its insertion and its removal. This results when the gear ratio causes the metal strip 130 to bridge the 55 brushes 138 at just the right time. As the division between the upper and lower typing zones will vary on different styles of work-forms, the gears are usually furnished to meet the requirements of the particular form to be 60 typed.

With a gear ratio proportioned for any one form, it is still possible to use the same gears for another work-form which has a different location of the division between the two zones. 65 This may be done by substituting an insulat-

ing disc having a greater or a less diameter. This insures a longer or a shorter circumferential travel, whereby its non-conducting surface may be made to register with the travel of the upper zone on the work-form. 70 Another variation is possible by attaching the insulating disc at a different radial location on the gear 125. A further variation of the work-form zones may also be met by lengthening or shortening the metal strip 130. 75

When the rotating members of this invention have been properly proportioned to function correctly with a given work-form, it is necessary that they always be correctly positioned for the insertion thereof. This is insured when the lug 146 abuts the tongue 145, as shown in Figure 2. Before inserting an initial work-form, therefore, care is taken to thus abut these two members. Thereafter each successive work-form, having the same length, will, when removed, leave these two members in abutment. This is because the forward travel of the work-form, after insertion, is always retraced in full before removal. The work-form is both inserted and removed, therefore, when in the location shown in Figure 2.

The foregoing description covers the use of a comparatively short work-form which is rear-inserted and removed, and in which the perforating operations are made possible through a single strip of metal. The idea embodied in this invention is also applicable for use with a so-called continuous work-form or tally strip, having captions printed in succession. To meet the latter conditions another metal strip may be added to the insulating disc and be positioned opposite the first. This will provide alternate areas on said disc, whereby the perforating machine is made operable or inoperable. Such alternate areas on the disc would be so proportioned as to register with the alternate zones on the continuous work-form, wherein the card-perforating operations are desired. 100

When using a continuous work-form the lug 146 would be removed from the gear 125 to permit complete revolutions in one direction of said gear and its attached insulating disc. Said disc also would first be properly registered with the alternate zones on the continuous work-form. This is accomplished by releasing the feed-rolls and properly positioning said form. After setting, the feed-rolls are again made operative to hold the form. This invention, therefore, is not limited to the use of an insulating disc having one metal strip. It could, in fact, have two or even more. 110

It is desirable to provide means for fine adjustment in order to accurately time the switch. This end may be simply attained by adjusting the brush-carrying angular plate 134, as indicated by the screw-and-slot con- 125

nection 133, 135, so as to retard or advance the period of contact.

Variations may be resorted to within the scope of the invention, and portions of the 5 improvements may be used without others.

Having thus described my invention, I claim:

1. In a combined typewriting and card-perforating machine, said typewriting machine having a rotary platen and means for electrically controlling said perforating machine, in combination, a master switch for controlling the working current, while a selected zone of a work-sheet crosses the typing 10 line, said switch including a traveling contact member and relatively stationary poles to co-operate therewith to make and break contact as it travels past the same, means for transmitting movement from the rotary platen to said contact member to operate the same, and means for timing the travel of said contact member with the movement of the platen, so as to close the switch during a predetermined interval of platen rotation to 20 coincide with the selected zone upon the work-sheet.

2. In a combined typewriting and card-perforating machine, said typewriting machine having a rotary platen, a platen-frame, 30 a platen-carriage and means for electrically controlling the perforating machine, in combination, a master switch to be mounted upon the platen-frame, for controlling the working current while a selected zone of a work-sheet 35 crosses the typing line, movement-transmitting means between the rotary platen and said switch for positively controlling the latter from the platen, means for timing the operation of the switch, so as to close the same during a predetermined interval of platen rotation to coincide with said selected zone, and flexible connections to conduct the working current over said switch while the carriage is freely movable.

3. In a combined typewriting and card-perforating machine, said typewriting machine having a rotary platen, a platen-frame and means for electrically controlling said perforating machine, in combination, a rotary master switch mounted upon the platen-frame for controlling the working current while a selected zone of a work-sheet crosses the typing line, a train of gears between a platen-shaft and said rotary switch to allow 50 the platen to operate the switch, and means for timing the operation of the switch with the rotation of the platen, so as to close the switch during a predetermined interval of platen rotation to coincide with said selected zone upon the work-sheet.

4. In a combined typewriting and card-perforating machine, said typewriting machine having a rotary platen and means for electrically controlling said perforating machine, in combination, a rotary master 65

switch for controlling the working current, including a rotary contact member formed with a disk of insulating material and a metal contact face thereon, and including relatively stationary brushes to co-operate with said contact member to periodically make and break contact, and means for positively transmitting platen rotation to actuate said contact member in a manner to close the switch during a predetermined interval of platen rotation to coincide with a selected zone upon the work-sheet.

5. In a combined typewriting and card-perforating machine, said typewriting machine having a rotary platen, a platen-frame 80 and means for electrically controlling the perforating machine, in combination, a rotary master switch mounted upon the platen-frame for controlling the working current as a selected zone of the work-sheet crosses the 85 typing line, speed-reducing means for positively transmitting platen rotation to said rotary switch when said zone requires a plurality of platen revolutions, and stop means arranged between said rotary switch and said platen-frame for determining initial position of the platen, so that the operative period of the switch will coincide with said selected zone upon the work-sheet, which is inserted to be gripped by usual feeding means at the 90 rear.

6. In a combined typewriting and card-perforating machine, said typewriting machine having a rotary platen, a platen-frame and means for electrically controlling the 100 perforating machine, in combination, a master switch mounted upon the platen-frame for controlling the working current while a selected zone of a work-sheet crosses the typing line, a bracket for mounting the switch 105 upon the platen-frame adjacent the platen-shaft, a gear associated with the switch, and another gear mounted upon the platen-shaft, said gears to be co-operatively engaged when the bracket is in place to positively control the switch, so as to close the same during a predetermined interval of platen rotation to coincide with said selected zone upon the work-sheet.

7. In a combined typewriting and card-perforating machine, said typewriting machine having a rotary platen and means for electrically controlling the perforating machine, in combination, a rotary master switch for controlling the working current while 115 a selected zone of a work-sheet passes the typing line, said switch including a rotary contact member, relatively stationary brushes to co-operate therewith to make and break contact and means for adjusting said brushes relatively to said contact member to retard or advance the action thereof, and means for controlling the switch from the platen, so as to close the same during a predetermined 120 interval of platen rotation to coincide with 125 130

said selected zone upon the work-sheet, said brushes adjustable to correctly time the switch.

8. In a combined typewriting and card-perforating machine, said typewriting machine having a platen, a platen-carriage and means for electrically controlling said perforating machine, including a master switch geared directly to said platen, means for controlling the switch from the platen line-space movements in order to close the circuit while a selected zone of a work-sheet is being written, so as to concurrently operate the perforating machine, and adjustable means for timing the operation of the switch with the platen movement.

9. In a combined typewriter and card-perforator, a platen for the typewriter, and electric means for controlling said perforator by a line-spacing movement of said platen, including a switch, and also including mechanism connecting the switch to said platen and automatically effective to operate the switch and stop and start the perforator.

10. In a combined typewriter and card-perforator, a platen for the typewriter, a working circuit, a switch therefor, and gearing connecting the platen to said switch to control the perforator from the line-space movements of said platen during the time predetermined zones of a work-sheet occupy the typing line of said typewriter.

11. In a combined typewriter and card-perforator, a platen for the typewriter, an electric circuit for operatively connecting the perforator with said typewriter, a switch in said circuit, and mechanism connecting the switch with said platen, including means for closing said switch during predetermined portions of line-space travel of said platen.

12. The combination with a card-perforator and a typewriter having a platen, of connecting means between the perforator and the typewriter for controlling the perforator by the typewriter through the line-spacing movements of said platen, said controlling means including a movable member responsive to said platen movements, and operative to put the perforator into and out of operation.

13. The combination with a card-perforator and a typewriter having a platen, of connecting means between the perforator and the typewriter for controlling the perforator by the typewriter through the line-spacing movements of said platen, said controlling means including a movable member responsive to said platen movements, and also including a device interpolated between the platen and the movable member to determine the distance traveled by the platen, said movable member being automatically effective to put the perforator into and out of operation.

14. The combination with a card-perfora-

tor and a typewriter having a revoluble platen, of connecting means between the perforator and the typewriter for controlling the perforator by the typewriter through the line-spacing movements of said platen, 70 said controlling means including a rotatable member responsive to said platen movements, and also including gearing interpolated between the platen and the rotatable member to predetermine the relative peripheral 75 travel of said member as compared with the line-spacing travel of the platen, said rotatable member being automatically effective to put the perforator into and out of operation.

15. The combination with a card-perforator and a typewriter having a platen, of connecting means between the perforator and the typewriter for controlling the perforator by the typewriter through the line-spacing movements of said platen, 80 said controlling means including a member responsive to said platen movements and effective to put the perforator into and out of operation, and means for adjusting the controlling member with reference to said platen. 85
